GRADE STRIKER

Adryl W. Gardner and Palmer Wrockloff, Redlands, Calif., assignors to Gardner-Byrne Construction Company, Redlands, Calif., a partnership

Application January 30, 1946, Serial No. 644,293

11 Claims. (Cl. 37—108)

1

This invention is a grade striker for surfacing soil, subgrade and other surfacing material and method of operation. The present day requirements of long and wide runways for airplane takeoff, extensive areas for airplane landing mats, wide roadways and other areas of surfacing material, necessitate machines operating on a large area at one run of machine over such surface. Hence this machine is developed to work a wide swath of surfacing material at each run over the area to be worked.

In preparing the large areas of ground now used for the above mentioned purposes, a common practice is to cut and fill by use of earth moving equipment of large capacity, with bulldozers, scrapers, etc., to work the surface to a rough grade. Engineers and surveyors set lines of stakes in rows marking the grade desired. In airplane fields of large area provision must be made for water runoff and drainage and there must be no abrupt change in slope, which might adversely affect airplanes in takeoff or landing.

The grade stakes set by the engineers may be in rows 25 feet apart each marked to desired grade and the stakes may be 20 to 30 feet apart in the rows. With a bulldozer or scraper a sinuous or serpentine path is graded, twisting on one side and then on the other of the sequence of stakes. This produces the approximate grade adjacent to the row of stakes and on both sides of each row. The wide space between the narrow path along the line of stakes is left very irregular as to soil surfacing material and contour.

For rows of stakes 25 feet apart the present machine spans 23 feet in each run. The grade striker employs a self-driven vehicle from which is suspended a transverse bridge or truss frame: and on the outer ends of the bridge are runners or shoes which rest upon and slide on the ground along the line of stakes. The bridge carries from the bottom cord a series of striker scraper blades, which are arranged with plow-like diverging blades at the center line. A set of diverging blades strikes the surface material outwardly from the center line and adjacent the shoes or skids are blades sweeping material inwardly. The striker blades shift the surface material above the grade line laterally filling the low spots and forming a series of small windrows or lines of piled up surface material. The bottom cord of the bridge or truss also has displaceable material pusher drifter blades set in front of the diagonal striker blades. These drifter blades may be turned upwardly out of drifting position when the machine functions to strike the

2

surface material sidewise. When the drifter blades are turned down they engage the material of the windrows and drift this lengthwise of the machine run. This action causes deposit of more material in the low spots and accumulates the surplus material in transverse mounds for removal by scrapers or trucks.

An important feature of the invention is the adjustable connection between the skid shoes and the bridge with its striker and drifter blades. This connection on each side is power operated to regulate the depth of cut of the blades. The bridge skid shoes and blades are connected to the vehicle to provide a front end pull on the striker assembly. The vehicle has power jacks for raising and lowering the front end, tilting such front end sidewise either way. The bridge, skid shoes and blades as a unit may be raised, and lowered or tilted sidewise to either side of the vehicle.

20 A transverse leveling or inclination gage is provided for the striker and drifter blade mounting. Sometimes the engineers set the grade stakes at one side only of an area requiring many trips of the striker to surface the material. If there is a lateral slope to be worked, specifications of slope are given the machine operator. The procedure usually is to set the skid shoes to travel on the graded surface along the line of stakes and by the side inclination gage the remote shoe is set to ride on the ground surface, and hence the bridge with its blades adjusted to the desired cross slope. This side slope may change gradually in a long machine run, hence the gage is positioned for ready inspection by the operator.

35 In the method of surfacing in reference to a preset grade the surface material is swept sidewise in relation to the grade as adjusted by the position of the skid shoes thereby depositing material in low spots or forming a series of windrows with the surface material. Then the run or part of the same is again traversed by the machine with the pusher blades in operative position. This develops a rolling and substantially uniform lateral spread of the pushed material, causing the deposit in low spots and cross mounds of surplus material. These mounds are removed by conventional earth removal equipment.

40 The invention is illustrated in connection with the accompanying drawings in which:

Fig. 1 is a side elevation of the grade striker taken in direction of the arrow 1 of Fig. 2 showing part of the transporting and power supply vehicle, detail parts being omitted.

Fig. 2 is a plan taken in the direction of the arrow 2 of Fig. 1 detail parts being omitted.

Fig. 3 is a broken front elevation on the lines 3-3 of Fig. 2, detail parts being omitted.

Fig. 4 is an enlarged side elevation of one skid shoe taken in the direction of arrow 4 of Fig. 5, remote parts being omitted.

Fig. 5 is a vertical section on the line 5-5 of Fig. 4.

Fig. 6 is an elevation of the front end taken in direction of arrow 6 of Fig. 7, remote parts being omitted.

Fig. 7 is a vertical section on line 7-7 of Fig. 6 in the direction of the arrows.

Fig. 8 is a vertical section on line 8-8 of Fig. 6 in the direction of arrows.

Fig. 9 is a longitudinal vertical section of the bridge and striker blade assembly, parts being omitted, on line 9-9 of Fig. 10, in direction of arrows.

Fig. 10 is an elevation taken in direction of arrow 10 of Fig. 9.

Fig. 11 is a detail front elevation taken in direction of arrow 11 of Fig. 12 of the mounting of drifter and striker blades.

Fig. 12 is a vertical longitudinal section on line 12-12 of Fig. 11.

Fig. 13 is a partial elevation similar to Fig. 1 illustrating wheels substituted for sliding skid shoes.

In the general views of the machine of Fig. 1, 2, and 3 part of the supporting, moving and power supply vehicle is indicated by assembly 25, showing one pair of a set of driving wheels 26 and steering wheels 27. An elongated part of the chassis 28 of substantial construction connects the axle of the front wheels 27 and the main part of the vehicle 29, being conventional has the power plant, drive to wheels 26 and most of the control devices. A pair of separately acting longitudinal lever beams 30 are carried by aligned transverse fulcrums 31 on the forward end of chassis 28 and the rear ends are raised and lowered by a jack 32 connected to chassis 28. Lever beams 30 are pivoted at their forward ends to a front transverse pulling and tilting bar 33.

Bar 33, note details Figs. 6, 7, and 8, has a central part 34 square in cross section and is connected with the beams 30 by pintles 35 in the ends of the cross beam. A central longitudinal gusset plate 36 has a square bearing opening 37 rounded at the edges, which bearing forms a central bearing for transverse bar 33 and lugs 38 on the bar prevent endwise slippage. Attached to the front edge of the gusset plate 36 is a front end plate 40 which is parallel to the bar 33. A flat top plate 41 is attached to both the gusset plate 36 and end plate 40.

Two pulling beams 45 are secured at their front ends 46 to both the end plate 40 and top plate 41 and thus have a pulling connection to bar 33 and lever beams 30. A lifting and lowering jack 50 is attached to the rear portion of each beam 45 and such jack is power operated under control of the operator. The jack 50 is a conventional type as used on earth moving machines.

A transverse bridge or truss assembly 55, note Figs. 1, 2, and 3, and detail Figs. 9, 10, is hung by hangers 56 from the rear portion of pulling beams 45. The bridge 55 may consist of an upper chord 57, a lower chord 58, strut 59 and brace bars 60. Shims 61 are fitted between the strut and lower chord and conventional steel shapes may be used to form the bridge. When

the shims are removed, the bottom cord may be slightly arched upwardly and substitute shims used when it is desired to grade strike to a camber. For large area working the bottom cord is usually straight.

The skid shoe assembly 70, note Figs. 1, 2 and 3 and detail Figs. 4, and 5, of which there is one on each side, has two vertical longitudinal side plates 71 shown connected at the bottom by a channel 72, and bottom plates 73, to which are attached wear plates 74. An eccentric pin 75 connects the two side plates 71 and functions in adjusting the riding relation of the skid shoes and bridge.

Each lateral end of the bridge 55 terminates in a longitudinal shoe guide beam 80 riding between the side plates 71 of the shoe and a box-like bearing structure 81 extends upwardly from beam 80. This box 81 has a circular bearing opening 82, the center of which is off center in relation to eccentric pin 75. A cylinder 83 is journaled in the bearing opening 82 and rotates on pin 75 and has a rotation arm 84 attached thereto illustrated located between the side plates 71 of the shoe. A jack assembly 85 is indicated with a hydraulic cylinder 86 pivotally connected to guide beam 80 and having a piston rod 87 pin connected to arm 84. Control hydraulic pipes etc. lead from the cylinder of the jack to the vehicle for using its power.

As the bearings 82 are preferably in the transverse center line of the bridge the rotation of the bearing cylinder 83 in relation to eccentric pin 75 will raise or lower the skid shoe 70 relative to the bridge.

The striker blade assembly 90, note general Figures 1, 2, 3 and detail Figs. 9, 10, 11 and 12 is indicated as having a central material diverting plow 91 (note Fig. 2), a series of blocks 92 for spreading material sidewise, one pair of blades 92 have rearward extensions 93 to form windrows outside the vehicle drive wheels 26 and converging blades 94 adjacent the skid shoes. The striker blades are indicated bolted to angles 95 attached to the bottom chord 58 of the bridge.

Drifter blades 97 are located across the lower edge of the bridge and forward of the leading edges of the striker blades and are indicated as turnable on pintles 98 on brackets 99 on the bottom chord of the bridge. The pusher blades are in several sections so that the operator may rotate them from inoperative raised position to lowered material drifting position. The drifter blades 97, when in operative drifting position, receive a thrust support from the leading edges of the striker blades 92 as shown in Fig. 12.

A lateral slope gage 105, note general Figs. 2 and 3, is indicated of a fluid level type, having a transverse pipe 106 located in the bridge and parallel to the bottom chord. Risers 107 at each end have sight gages 108 positioned for convenience of observation by the machine operator.

The general manner of operating is substantially as follows: For movement over the ground 65 without working, the jack 32 may be used to raise the front end of lever beams 30, which hoists the front end of pulling beams 45. The jacks 50 mounted on the part 28 of chassis can lift the rear ends of beams 45 and hence raise the bridge 70 55 and its assembly of striker and drifter blades well above the ground surface.

Usually the machine is to work the surface between two lines of stakes setting the grade on both sides of the machine run and the ground 75 adjacent the rows of stakes has been graded by

conventional equipment. When the machine is lined up for a run, the jacks 32 and 50 are manipulated to bring the skid shoe 70 in contact with the graded line of the stakes and jacks 85 are used to bring the striker blades to operate on the desired grade side slope, if any. The wear plates 74 and hence the shoes do not carry all the weight of the bridge assembly 55; but this is supported in part by jacks 32 and 50. However, sufficient pressure is brought on the striker blades to cut the surface material above grade, move this sidewise to deposit in low spots and form a series of windrows of the surplus material.

Should there be low unfilled places the bridge and striker blades may be raised, the machine run backward to a section of the run having surplus material in windrows. The blades are again set to grade and the drifter blades brought into operative position, the machine driven forward to drift such surplus material over the unfilled areas. While the machine travels the jacks 85 acting on the shoes may be operated to raise the blades slightly above grade to spread the surplus material. The machine may be again backed and striker blades worked over sections of the run requiring considerable fill.

If the "cuts" are greater than the "fills" the windrows show the amount of surplus material. The machine then makes a run with the drifter blades shoving such surplus into a succession of cross mounds lengthwise of the run, which mounds may later be removed by standard equipment.

Should a grade line be adjacent one line of stakes only the shoe on such side is set to grade, then by using the sight gage 105 the bridge is inclined, should there be a side slope, to the specification and the other shoe adjusted to bear on the unworked surface or be carried above the surface, if desired. The machine then works a run striking the surface material to grade. In the next parallel run one shoe travels on the section just worked. The side slope is maintained by the operator checking the gages 105 by the specification. As the machine traverses its run the side slope may be altered in accordance with the specifications of the job. The jacks 85, which regulate the relation of the shoes and blades, hence may make adjustments as the blades wear. When the wear of the blades becomes excessive, they may be readily removed and replacement blades substituted. In making a run with the skid shoes on one side sliding on the established grade line it sometimes happens there is so much surplus material that the shoe on the other side cannot be lowered to grade but must slide on material having an uneven surface. In such case the bridge and blades may be lowered to the grade line and the operator checking by the sight gage 108 may maintain the correct grade cut and side slope.

When the machine is moved from one job to another the bridge assembly may be disconnected by unbolting the hangers 56 from the pulling beams 45; also the hydraulic connection to jacks 85 of the shoe adjustment must be disconnected. The bridge with its associated parts may then be transported by truck; and if the distance from one job to the next is not too great, the vehicle may make the journey under its own power.

An equalizing auger assembly 120 is used with the drifting or bulldozer blades 97 and is located forward of the drifters 97 and transverse of the machine (note Figs. 1, 2 and 3) with the outside ends 121 journaled on the inside of the side plates 71 of the shoe assembly 70. The auger blades

122 have the helix reversed as to opposite sides of the machine and are sufficiently above the cutting edge of the striker blades 91 so as not to interfere with the lateral striker action on the mineral aggregate.

5 A counter shaft 123 is located above the auger blades 122 and is journaled in struts 124 extending upwardly and forwardly from the truss assembly 55. A flexible drive 124' is indicated 10 transmitting rotation from the counter shaft 123 to auger blades 122, and power is transmitted through a gear box 125 from a main shaft 126, driven by an engine 127 provided with a clutch and change speed gears, if desired.

15 The auger is so located as not to interfere with raising and lowering of the drifting blades 97, and is operated when these are lowered to drifting position to shift the surplus material from the windrows made by the striker 90 for action 20 by the drifters 97.

25 Fig. 13 illustrates wheels 130 substituted for channels 72, bottom plates 73 and wear plates 74. Wheels 130 are journaled in side plates 71 of the shoe assembly 70 and roll on the mineral aggregate.

We claim:

1. A grade striker having a vehicle with a longitudinally extending chassis, the vehicle having driving and steering wheels, longitudinal lever beams fulcrumed on the forward part of the chassis, a transverse bar pivotally connected to the forward ends of the lever beams, a rigid transverse structure pivotally connected to said bar, pulling beams rigidly attached to such transverse rigid structure, a transverse bridge having a rigid connection to the rear ends of the pulling beams, means interconnecting the vehicle and the lever beams to incline such beams as to the longitudinal direction, means interconnecting the vehicle and the pulling beams to incline such beams as to a longitudinal direction and aggregate means mounted on the bridge.

2. As claimed in claim 1, a shoe on each end of the bridge having means for contacting the subgrade, and means to raise and lower each shoe in reference to the end of the bridge to which it is connected.

3. A grade striker including a vehicle, a bridge extending laterally therefrom, a shoe bearing on the subgrade, an adjustable connection for various adjustments between the shoe and the bridge to operate the shoe on a subgrade and maintain the bridge a constant space from such subgrade for any particular adjustment, and material aggregate working means mounted on said bridge.

4. A vehicle, a bridge extending laterally therefrom, striker blades carried by the bridge positioned diagonally as to the forward travel of the vehicle, and a drifter blade mounted on the bridge and movable from a raised to a lowered position to drift aggregate in front of the striker blades, the forward ends of the striker blades being positioned to develop a thrust support to the drifter blade when in lowered drifting position.

5. A device as in claim 4 an equalizing auger on the bridge forward of the drifter blade, with means on the vehicle to rotate the auger.

70 6. A vehicle having a transverse bridge, with aggregate moving means mounted thereon, a shoe to contact the subgrade, a connection between the bridge and the shoe including an eccentric whereby the shoe may be raised and lowered for various adjustments in reference to the

subgrade and the aggregate moving means and the shoe retained in constant relation each to the other for any particular adjustment.

7. A grade striker including a vehicle, a transverse bridge connected to the vehicle, material aggregate working means on the bridge, a shoe to bear on the subgrade, an adjustable connection between the bridge and the shoe to operate the shoe on the subgrade, means to actuate said adjustable connection while the vehicle is in motion, the shoe contacting the subgrade and the aggregate working means operating on the aggregate.

8. A grade striker including a vehicle, having a station for an operator, a bridge extending laterally from the vehicle, means adjustably connecting the vehicle and the bridge, a shoe to bear on a subgrade, an adjustable connection between the shoe and the bridge to operate the shoe on a subgrade, means under control of the operator while at his station on the vehicle to operate the adjustable connection between the vehicle and the bridge and to independently operate the adjustable connection between the shoe and the bridge while the vehicle is in motion and material aggregate working means mounted on said bridge.

9. A device as in claim 8 the adjustable connection between the shoe and the bridge including an eccentric and a remote controlled jack to actuate said eccentric.

10. A grade striker having a vehicle with a longitudinally extending chassis, a transverse bar, means connecting the transverse bar to the chassis for raising and lowering said bar, a rigid transverse structure pivotally connected to said

5 bar, pulling beams rigidly attached to said transverse rigid structure, a transverse bridge having a rigid connection to the rear portion of the pulling beams, means interconnecting said chassis and the pulling beams to incline said beams in a longitudinal direction and aggregate moving means mounted on the bridge.

11. A vehicle having a transverse bridge with aggregate moving means mounted thereon, a longitudinal guide beam secured to the bridge, a shoe to contact a subgrade, a rigid structure forming part of the shoe and having part thereof in proximity to opposite sides of said beam to prevent lateral deviation of said shoe from the 10 direction of travel of said beam, means for various adjustments connecting the shoe and the guide beam to raise and lower the shoe relative to the guide beam and bridge.
